United States Patent Office

Des. 213,847
Patented Apr. 15, 1969

213,847

GRILLE

Edward C. Hallock, 86 Woodland Ave.,
Summit, N.J. 07901

Filed July 11, 1967, Ser. No. 7,764

Term of patent 14 years

Int. Cl. D25—01; D5—03

U.S. Cl. D54—2

FIG.1.

FIG.2.

FIG.3.

FIG.4.

FIG.5.

FIG.6.

FIGURE 1 is a plan view of a grille showing my new design, partially broken away to indicate indefinite length;

FIGURE 2 is a front elevational view thereof, partially broken away to indicate indefinite length and height;

FIGURE 3 is a rear elevational view thereof;

FIGURE 4 is a plan view of a modification of the grille showing my new design, partially broken away to indicate indefinite length;

FIGURE 5 is a front elevational view thereof, partially broken away to indicate indefinite length and height; and

FIGURE 6 is a rear elevational view thereof.

I claim:

The ornamental design for a grille, as shown and described.
